UNITED STATES PATENT OFFICE.

FREDERICK M. BECKET, OF NIAGARA FALLS, NEW YORK, ASSIGNOR TO ELECTRO METALLURGICAL COMPANY, OF NIAGARA FALLS, NEW YORK, A CORPORATION OF WEST VIRGINIA.

EXPLOSIVE.

1,310,466.

Specification of Letters Patent. Patented July 22, 1919.

No Drawing.

Application filed June 7, 1918. Serial No. 238,725.

To all whom it may concern:

Be it known that I, FREDERICK M. BECKET, a subject of the King of Great Britain, residing at Niagara Falls, in the county of Niagara and State of New York, have invented certain new and useful Improvements in Explosives, of which the following is a specification.

This invention is an explosive containing 10 as essential components a magnesium-silicon alloy, and an oxidizing agent. The oxidizing agent may be ammonium nitrate, or equivalents therefor, including nitrates of the alkali metals, barium and lead, chlorates 15 or perchlorates of the alkali metals including ammonium, or the like, or mixtures thereof.

I have found that the magnesium-silicon alloys, especially such as contain a preponderating proportion of magnesium, possess marked advantages for use in explosives as compared with other silicon-containing substances, such for example as the silicides of calcium and aluminum.

Typical magnesium-silicon alloys for use 25 in accordance with my invention may comprise:—

Silicon	10-40%
Magnesium	50-90%
Iron	up to 20%

The presence of iron in the alloy is not essential, being more or less incidental to the employment, as a convenient material 35 for making the desired alloy, of a high grade ferrosilicon. The alloy may be prepared for example by melting metallic magnesium together with ferrosilicon containing 80-85% of silicon, the melting being performed 40 under strictly non-oxidizing conditions, and preferably in an electric melting furnace. My invention is not limited, however, to the use of an alloy prepared in this manner.

The proportion of oxidizing agent will 45 of course depend upon the particular oxidizer used, as well as upon the specific composition of the magnesium-silicon alloy, it being essential only that the oxidizing agent should be in sufficient proportion to supply

the oxygen requirements of the explosive reaction. For example I may employ a composition containing:—

Magnesium-silicon alloy	5-20%
Ammonium nitrate	80-95%

55

Other ingredients may of course be introduced without departing from my invention.

A primary advantage of the introduction of magnesium into explosive mixtures follows from the great amount of heat liberated in course of its combination with oxygen. Magnesium metal, however, particularly when very finely subdivided and when existing under the conditions obtaining in the explosive mixture, is somewhat lacking in 60 stability and liable to slow oxidation. I have found on the other hand that the magnesium-silicon alloys are sufficiently stable to permit of such use. In this respect the magnesium-silicon alloys are sharply differentiated from such alloys as those of silicon with calcium. For example calcium silicide corresponding substantially to the formula 65 CaSi is a fairly stable compound, but alloys of calcium and silicon containing a 70 material higher proportion of calcium than the above are comparatively unstable; consequently it has not proven practicable to increase the power of explosive mixtures 75 containing calcium and silicon by increasing the calcium content of the alloy component. This does not apply however to the magnesium-silicon alloys, which possess a sufficient degree of stability for the purposes indicated even when the magnesium content is decidedly higher than corresponds to the known silicide MgSi. Such compounds, irrespective of the presence or absence of iron or other components, may be defined 80 as alloys in which the magnesium is in excess 85 of the equimolecular proportion to the silicon.

A further advantage in the use of magnesium-silicon alloys arises as follows:— The magnesium component of the alloy requires for its oxidation only about one-half of the oxygen required by the silicon component. It follows from this that the higher 90 95

the relative proportion of magnesium in the alloy, the larger the permissible proportion of the alloy in the explosive mixture. It is therefore of great advantage in this connection that the magnesium-silicon alloys containing more than the equimolecular proportion of magnesium possess sufficient stability for use in explosive compositions.

Other advantages arising from the use of magnesium-silicon alloys in compositions of the kind above indicated follow from the relative lightness of these alloys and from the fact that the alloys are relatively brittle as compared with metallic magnesium, and are hence more easily pulverized to the requisite degree of fineness.

Copies of this patent may be obtained for five cents each, by addressing the "Commissioner of Patents, Washington, D. C."

I claim:

1. An explosive containing an oxidizing agent and a magnesium-silicon alloy.
2. An explosive containing an oxidizing agent and a magnesium-silicon alloy, the magnesium in excess of the equimolecular proportion to the silicon.
3. An explosive containing ammonium nitrate and a magnesium-silicon alloy.
4. An explosive containing ammonium nitrate and a magnesium-silicon alloy, the magnesium in excess of the equimolecular proportion to the silicon.

In testimony whereof, I affix my signature.

FREDERICK M. BECKET.
